UNITED STATES PATENT OFFICE

2,539,661

SOLVENT FRACTIONATION OF REFINED
GLYCERIDE OILS

Stephen E. Freeman, Pittsburgh, Pa., and Stewart W. Gloyer, Milwaukee, Wis., assignors to Pittsburgh Plate Glass Company, Allegheny County, Pa., a corporation of Pennsylvania

Application October 15, 1947, Serial No. 780,060

13 Claims. (Cl. 260—428.5)

1

The present invention relates to a method of separating oils composed essentially of glycerides of a mixture of higher fatty acids which are distinguished from each other primarily by the degrees of or the molecular arrangement of the double bonds in the hydrocarbon chains into fractions upon the basis of the unsaturation of the acid components.

One object of the invention is to provide a process of fractionating oils composed of glycerides of relatively saturated and unsaturated higher fatty acids which can be efficiently operated by continuous counter-current methods to obtain from a drying or semi-drying oil a relatively large proportion of oil especially adapted to use in paints and other coating media.

A second object is to obtain from a drying or semi-drying oil a fraction which is rich in the more saturated more solid components of the oil.

A third object of the invention is to provide a process of fractionating oils of the foregoing type in which fractionation of glycerides upon the basis of degree of unsaturation can be effected countercurrently in a single step extraction.

A fourth object is to provide a process of the foregoing type that can be operated without difficulty from emulsification of the oil and the polar solvent.

These and other objects will be apparent from consideration of the following specification and the appended claims.

It has long been recognized that glyceride oils and notably oils of the drying or semi-drying type were composed mainly of the glycerides of a plurality of higher fatty acids of varying degrees of unsaturation. The various fatty acid components of the glycerides differ in proportion with different oils and are influenced by such factors as climate, variety and so forth. However, soybean oil is a typical example of an oil which has drying properties but still, in its natural state is not entirely satisfactory for use as a coating composition.

Soybean oil is a mixture of glycerides of various fatty acids in which the fatty acids are in the following proportion:

Per cent

Linoleic acid	51.5
Oleic acid	34.4
Palmitic acid	6.8
Stearic acid	4.4
Linolenic acid	2.3
Arachidic acid	.6

2

The percentages designated are based upon the total of the acids the esters of which are present in the glycerides. It is a characteristic of the glycerides containing such mixture of fatty acids that the acid radicals are relatively uniformly mixed in the glyceride molecules. That is, each glyceride molecule will contain a plurality of different acid radicals. For example, the glyceride molecule may contain one oleic acid radical, one palmitic or stearic acid radical and a linoleic acid radical. There will be present also various other possible combinations of the different acids and there may be present small amounts of the triglycerides of single acids. These facts are established in Thorpe's Dictionary of Applied Chemistry, volume 4, pages 81 and 82 (4th edition). They are further established in an article by Hilditch and Jones published in the Journal of the Source of Chemical Industry, Transactions, pages 13 to 21, inclusive, of the January 19th issue, 1934.

It will be apparent with the large number of acids present in an oil such as soybean oil a great number of possible glycerides are present. Some of these, notably those containing considerable two or three of linolenic or linoleic acid radicals are susceptible of rapid drying when spread as films. These impart to the oil drying characteristics which have heretofore led to considerable use of the oils to replace a portion of the linseed oil in paints and varnishes. However, the natural oil is comparatively slow in drying and is not customarily employed as the sole drying oil component of a paint or varnish.

It has heretofore been proposed to subject a glyceride oil such as soybean oil composed of drying and non-drying glycerides to a process of fractionation in order to obtain a portion of superior drying properties and at the same time to obtain non-drying fractions of superior value for other purposes such as use in food products, e. g., shortenings, salad oils, butter substitutes or the like.

It has further been proposed to fractionate glyceride oils such as linseed oil and soybean oil and other oils comprising mixtures of glycerides of relatively highly saturated and relatively highly unsaturated acids into fractions upon the basis of the degree of unsaturation of acid radicals in the glycerides by means of selective solvents having a greater affinity for the more unsaturated glycerides. Solvents suitable for the purpose in general are of the class known as polar solvents. This type of process is broadly disclosed in U. S. Patent 2,200,391 to Stephen E. Freeman. The patent lists a large number

of polar solvents and describes methods by application of which suitability of a given solvent can be predicted with a considerable degree of accuracy. By application of the process as described in the patent, oils have been successfully fractionated upon an extensive scale. However, under some conditions certain difficulties have been encountered in the operation of the process. One such difficulty involves a tendency of certain of the oils, notably crude linseed and crude soybean oil, to form emulsions with the solvent employed in the extraction system.

One of the most convenient solvents for use in the process comprises furfural which is relatively abundant and inexpensive and which has many other characteristics rendering it valuable for use in the process described in the patent. However, in the extraction of crude linseed oil or crude soybean oil with furfural in order to obtain relatively saturated and unsaturated fractions much difficulty from emulsification has been encountered. When emulsification occurs, the oil and the solvent become so intimately associated that separation into phases cannot be attained within a reasonable period of time. Therefore, the volume of oil that can be put through a given piece of apparatus is greatly reduced. Countercurrent extraction methods then become impracticable. Perhaps batchwise operations, in which portions of emulsified oil and solvent could be left standing for long periods of time would be operable but these in general are not efficient or economical.

The present invention involves the discovery that the emulsification of the glyceride oils with selective polar solvents such as furfural in the fractionation of glyceride oils is largely due to the presence of certain non-glyceride components of the oil. These components are usually termed gum constituents. It has now been found that if these are removed or their concentration is sufficiently reduced, before the oil is subjected to extraction with the polar solvent, the difficulties with emulsification are substantially eliminated.

In order to obtain an oil which will not emulsify when it is countercurrently extracted with furfural or similar solvents, the oil may be subjected to alkali treatment known as refining, or in some instances, washing with water is sufficient. The oil when so treated can be put through an extraction column without appreciable tendency to emulsify with furfural.

The techniques of alkali refining and water washing have heretofore been developed for other purposes and are not here greatly departed from except in the subsequent application of solvent extraction to obtain the portions which are of especial interest to the paint and varnish industry from those portions of particular merit for use as food fats. The refining and washing technique is well understood by those skilled in the art and usually involves considerable degree of personal experience upon the part of the practitioners. The broad technique, however, has been delineated in various textbooks and publications available to the art. One such publication is Industrial Oil and Fat Products, A. E. Bailey, published by the Interscience Publishers Incorporated of New York, 1945. Probably the simplest technique which can be employed to obtain an oil suitable for the purpose of the present invention involves simple "degumming" by heating the oil in the presence of water in order to precipitate out phosphatides, protein and gummy or mucilaginous substances. This technique is described on page 501 of the text as follows:

"Certain oil impurities such as phosphatides, proteins or protein fragments, and gummy or mucilaginous substances, are soluble in the oil only in an anhydrous form, and can be precipitated and removed if they are hydrated. The hydration and removal of phosphatides from soybean oil has been described previously in connection with the solvent extraction of soybeans. Other vegetable oils, and particularly corn and cottonseed oils, are also sometimes subjected to a similar 'degumming' process prior to alkali refining, in order to reduce the refining loss.

"The water washing or degumming process is similar to continuous alkali refining except that warm water is used in place of the alkali."

15 The art of degumming by precipitation of the phosphatides and such like constituents by water as well as alkali refining are discussed in numerous other texts including Vegetable Fats and Oils by Jamieson, Second edition, copyrighted 1943 by the Reinhold Publishing Corporation, 330 W. 42nd St., New York, N. Y., pages 206 and 207; Fats and Waxes, by Hilditch, copyrighted by D. Van Nostrand Company, 8 Warren St., New York, N. Y., 1927 (see pages 180 to 197 inclusive).

20 In the practice of the present invention a glyceride oil which has been suitably refined to eliminate the tendency to emulsify, characterizing raw or natural oil and comprising a mixture of glycerides of fatty acids of varying degrees of unsaturation is subjected to fractionation into relatively highly saturated and relatively highly unsaturated portions in accordance with the technique described in the aforementioned U. S. Patent 2,200,391.

25 The oils contemplated as being within the purview of the invention include linseed oil, cottonseed oil, soya bean oil, corn oil, fish oil, whale oil and the like appropriately refined, but degummed or refined soybean oil and linseed oil are particularly contemplated because with the crude oils from which they are derived, emulsification is especially severe. Moreover, they are composed of glycerides of fatty acids of such nature that when properly fractionated, portions of exceptional value for use in coating compositions are readily obtained and at the same time, fractions of especial value for use in the preparation of food products or other uses are obtained as raffinates.

30 The solvents disclosed in the U. S. Patent 2,200,391 are contemplated as being within the purview of the present invention. However, furfural, all points considered, seems to be the most practical. Other very satisfactory solvents include methyl acetoacetate, ethyl acetoacetate, acetyl acetone, nitromethane, nitroethane, methyl cellosolve, methyl formate, methyl levulinate, glycol diacetate.

35 The technique of extraction is susceptible of considerable variation but may be outlined broadly as follows:

40 The solvent should be employed in a range of 3 to 30 parts by volume per part of oil to be treated. The preferred range is approximately within the limits of 6 to 15 parts per part of oil treated. However, these limits are set more by the economics of solvent evaporation than by behavior of the solvents with respect to the oil to be treated.

45 It will be apparent that the temperatures of operation will vary for different solvents, the proportion of solvents and with the oil to be treated by given solvents. For example, soybean

oil which has been refined may be extracted with very satisfactory results within a temperature range of about 109 to 111° F. Variation of a few degrees in either direction is contemplated. In any event, the temperature at which a satisfactory proportion of extract is obtained can be determined quite readily. The system should be so operated that the oil is but partially miscible with the solvent employed. It will be apparent that if the temperature is raised unduly, all of the oil or substantially all of it will go into solution; under which conditions no appreciable fractionation is possible. If the temperature is too low of course only small extract fractions consisting largely of by-products will be obtained and for most purposes the process is undesirable. Assuming that soybean oil is to be treated, the best temperature is that at which a fraction of about 40 to 75% of the oil passes into solution as an extract. When the system is so operated the extract will be greatly enhanced in iodine value. Ordinary soybean oil has an iodine value of approximately 130 to 138. These improved fractions have iodine values of approximately 150 to 156 or 157. Although these values still are substantially less than those of ordinary linseed oil, they dry almost as fast as the latter. It probably is practically impossible to obtain an appreciable fraction from soya oil of an iodine value corresponding to that of linseed oil (about 180) because of the uniform distribution of the saturated and but slightly unsaturated acid radicals in the glyceride molecules. However, this fact is not very important since the extract oil dries nearly as well and in certain respects even better than linseed oil.

A suitable embodiment of apparatus for use in the practice of the invention is diagrammatically illustrated in the single figure of the drawings in which like numerals refer to like parts throughout.

The apparatus as shown includes a vertical column 10 in which the extraction of the oil with the polar solvent may conveniently be conducted. This column is packed with Raschig rings, Berl saddles or other packing designed to assist in obtaining thorough contact of oil and solvent medium. It may be of any convenient length but preferably it is 70 or more feet in length. Relatively long columns are especially desirable for the fractionation of soybean oil since the latter appears to require considerable stages of contact with the polar solvent in order to attain equilibrium conditions. The column may be 150 ft. in length or even longer. There appears to be no particular upper limit of length other than such as may be imposed by the costs of construction and such factors.

Contiguous to the column are disposed a container 11 for the storage of an appropriate amount of the oil to be extracted and a container 12 for the storage of polar solvent such as furfural. A third container 13 is optional and is for the storage of naphtha which may be employed in admixture with the polar solvent as it is fed into the extraction column 10. It is to be reiterated that the use of naphtha as an adjuvant is optional and may be dispensed with if so desired. Such container would be joined to column 10 by line 14 having a preheater 14a.

The feed of oil to the column 10 is effected at some intermediate point and may as shown in the drawings, be near the middle of the column 75

but considerable variation in either direction is admissible. It may, for example, occur at any point between the lower quarter and the upper quarter. Feed of oil to the column is effected through a conduit 15, having a distributor head 15a in the column. A portion of line 15 may be coiled as shown at 16 and disposed in a pre-heater shell 17. Fluids designed to bring the glyceride oil to appropriate temperature are circulated through the shell by means of inlet conduit 18 and outlet conduit 19.

15 A similar arrangement is provided for the control of the temperature of and the feeding of selective polar solvent into the zone near the top of the column. A feed line 22 from container 12 for this purpose is indicated diagrammatically in the drawings and the feed is conducted through a temperature conditioning apparatus which may function either as a preheater 23 or as a cooler 20 as climatic conditions or the nature of the oil may dictate.

In order to maintain the desired temperature within the column or to obtain a suitable gradient of temperature between the top and bottom, suitable temperature conditioning devices may be provided. Such devices would include jackets (not shown) disposed about the column and being provided with suitable conduits for circulation or a temperature conditioning medium. For 25 large installations, external heat exchange elements are more suitable. Such devices are illustrated at 24 and 26 in the drawings and may include coils 27 and 28 appropriately connected by means of conduits 27a and 28a with the column 30 35 40 45 so that portions of oil and solvent may be drawn off heated or cooled and returned to the column. Any convenient number of coils may be so provided. The coils are installed in jackets or shells 29 and 30 which conveniently are provided with inlets 31-32, and outlets 33-34 for the circulation of a liquid medium which may be either hot or cold as conditions may require.

It will be apparent that the glyceride oil, after 45 introduction into the column is contacted intimately with the downwardly flowing solvent introduced slightly below the top of the column through the line 22. The raffinate oil freshly washed with the solvent of highest purity and saturated with a small amount of the solvent is drawn off at the top of the column above the point of inlet of selective solvent through line 33. This raffinate fraction of course comprises the relatively more saturated glycerides especially suitable for use in food products. Raffinate solution passing 50 55 60 65 through line 36 may conveniently be subjected to distillation in a still 38 of conventional design for the removal of the major portion of the solvent. The raffinate oil is drawn off through line 41 and may then be passed through a steam stripper 42 for the complete and thorough removal of any solvent which may be dissolved therein. The finished raffinate is drawn off through line 43. Solvent from the oil as obtained in the still 38 is drawn off through line 44, preferably in vapor 70 75 phase and is condensed in a suitable condensing apparatus 46. It may be passed through line 48 to the container 12 for reuse in the system. Such recycling is optional but usually is dictated by the economics of operation.

Extract solution of the more unsaturated glycerides dissolved in the polar solvent is drawn off from the bottom of the column through the line 49. All of it may be passed through a still 54 75 for the removal of solvent and the recovery of

7
the oil dissolved therein. The solvent in vapor phase passes off through line 55 to a condenser 56 in which it is recovered and then returned through line 57 and 48 to storage container 12. The extract oil comprising the highly unsaturated glycerides passes off from the still through lines 58 to a second stripper 59 in which it is subjected to a steam distillation operation in order to effect more thorough elimination of any solvent contained therein. The solvent free extract oil may pass to storage through line 60 or if it is desired a portion of the stripped oil may be fed as reflux to the bottom portion of column 10 through line 60A.

In some instances the iodine value of the extract, as obtained from the system may be improved by recirculating a portion of the extract oil from which the solvent has been partially or completely removed. The amount of oil so refluxed will vary with the iodine value desired in the extracted oil and the economics of operation. In general, a reflux of .1 to 5 parts of extract oil per part of oil treated is contemplated. Preferably, this refluxed or recirculated portion of the oil is introduced near but above the bottom of the column and the point at which extract solution is withdrawn. For purposes of maintenance of such reflux, a portion of extract solution may be drawn off from the line 49 through a line 61 and is then passed through a still 62 similar to the still 54 for evaporation of solvents. The solvent from this portion of the oil, of course, is recovered, being taken off through a line 63 and condensed in condenser 56. The condensate is returned to the container 12 through lines 57 and 48. Usually the reflux fraction will be reduced to at least 50% solvent in the still 62. The refluxed portion of oil is drawn off through line 67 and may, if desired, be passed through a temperature conditioning device 68, e. g., a coil in which the temperature is brought to appropriate value for introduction into the column. The reflux fraction passes from the device through line 69 to the distributor head 71 within the column slightly above the bottom thereof.

If prepared, a reflux of naphtha from a container 13 may be substituted for all or a portion of the reflux of oil into the bottom of the column 10. This reflux should not be so great as to impair the yield of extracted oil in the polar solvent and preferably is within a range of .1 to 2 parts based upon the feed oil for this purpose.

In order to maintain the flow of liquids in the system, pumps may be required. The positioning of and the number of these pumps will depend upon the relative positions of the various pieces of apparatus which of course will be dictated by local conditions and the judgment of the engineer designing the apparatus. Valves for shutting off the flow of liquids or for proportioning the flow of liquids throughout lines or conduits are also desired. These may be introduced in any of the lines. Some of them are indicated in the drawing by the letter V.

In the operation of the apparatus shown and described, the glyceride oil, e. g., soybean oil which has been subjected to a refining operation such as degumming by heating in the presence of water and/or alkali refining is passed into the column 10 through the line 15. Simultaneously, a selective polar solvent, e. g., furfural is passed in at the top of the column through the line 22. If desired, 1% up to 15% of naphtha may be added to the oil before extraction though

8
this is not an essential feature of the invention. Under some conditions, separation of the phases is promoted thereby.

The raffinate oil passing off through the line 36 is subjected to distillation in the still 38 to remove solvent such as furfural which is condensed in the condenser 46 and may be recycled. The raffinate oil comprising glycerides of relatively low degree of unsaturation, e. g., 110 or thereabouts may be further steam stripped in the stripper apparatus 42. The resultant product is very suitable for use in food products. Of course, it can be hydrogenated in order further to reduce the iodine value thereof and thus to improve the hardness of the product. The products obtained by hydrogenation of raffinate extract herein disclosed is of superior value from the standpoint of stability, taste and such like factors as compared with similar products obtained by hydrogenating the whole soybean oil.

15 The extract phase passes out through line 49 and comprises most of the solvent introduced into the system as well as the more unsaturated glycerides dissolved therein. All of it may be passed through the still 54 to remove the major portion of the solvent after which it is completely stripped of solvent in the stripper 59. Of course, the solvents so recovered may be returned to the system. The extract oil will have 20 iodine value above 140 and usually above 150.

25 The extract oil, a reflux portion is taken off through line 69 and is a certain portion of the extract solution partially or completely freed of solvent in still 62. A reflux could be taken from the oil passing out of still 54 thus eliminating still 62. However, greater flexibility of operation is attained with two stills. The reflux is returned to the lower portion of the column 10 through line 69. The amount is within a range of .1 to 5 volumes per volume of oil from container 11.

30 If it is desired to increase the iodine value of the extracted oil, a reflux portion is taken off through line 69 and is a certain portion of the extract solution partially or completely freed of solvent in still 62. A reflux could be taken from the oil passing out of still 54 thus eliminating still 62. However, greater flexibility of operation is attained with two stills. The reflux is returned to the lower portion of the column 10 through line 69. The amount is within a range of .1 to 5 volumes per volume of oil from container 11.

35 If desired this reflux oil may be admixed with or replaced by a reflux of naphtha from the container 13. The proportion may be 0.1 to 2 volumes per volume of oil from container 11. In any event, the amount of naphtha is maintained sufficiently low that there is no appreciable separation of a separate naphtha phase in the system.

40 The following constitutes specific examples

45 illustrating the operation of the apparatus as herein shown and described.

50

Example 1

[Oil used, alkali-refined linseed oil. Solvent used, furfural.]

60	Conditions of Operation	Gal./hr.	Ratio—Parts per Part Feed Oil
Oil feed to column.....		47	
Furfural feed to column.....		343	7.3 to 1
Reflux oil feed to column.....		34.5	0.73 to 1

55 Column temperature: Top, 88° F. Bottom, 81° F.

70	Products	Per Cent Yield	I. V.	Line
Extract.....	78.5	195.6	60	
Raffinate.....	21.5	122.7	43	
Original Oil.....		179.5	14	

Example 2

[Oil used, alkali-refined soya oil. Solvent used, furfural.]

Conditions of Operation	Parts/min.	Ratio—Parts per Part Feed Oil
Oil feed to column	20	
Solvent to column	166	8.3 to 1
Reflux oil feed to column	22	1.1 to 1

Column temperature: Top, 109° F. Bottom, 111° F.

Products	Per Cent Yield	I. V.	Line
Extract	57.3	155.0	60
Raffinate	42.7	110.4	43
Original oil		136.5	14

Example 3

[Oil used, water degummed soya oil. Solvent used, furfural.]

Conditions of Operation	Parts/min.	Ratio—Parts per Part Feed Oil
Oil feed to column	20	
Solvent feed to column	166	8.3 to 1
Reflux oil feed to column	22	1.1 to 1

Column temperature: Top, 109° F. Bottom, 112° F.

Products	Per Cent Yield	I. V.	Line
Extract	58.8	156.2	
Raffinate	41.2	111.6	
Feed oil		136.6	

Example 4

[Oil used, refined soybean oil (water degummed). Solvent used, furfural (naphtha sat.)+a naphtha of 8 to 11 carbons.]

Conditions of Operation	Parts/min.	Ratio—Parts per Part Feed Oil
Oil feed to column	30	
Solvent feed to column	600	20
Reflux naphtha feed to col.	68	2.3
Oil reflux to column	0	0
Solv. dilution with naphtha	60	2

Column temperature: Top, 135° F. Bottom, 135° F.

Products	Per Cent Yield	I. V.
Extract	62.0	150.0
Raffinate	38.0	104.0
Original oil		132.2

It will be apparent to those skilled in the art that the embodiments of the invention herein shown and described are by way of illustration. Numerous modifications may be made therein without departure from the spirit of the invention or the scope of the appended claims.

We claim:

1. In a process of treating a natural glyceride oil to separate therefrom a portion which is substantially enriched in one or more components of the natural oil, the steps which comprise removing the gum from the natural oil, then extracting out said portion by countercurrently flowing furfural through the oil, the resultant system of oil and furfural being maintained at a temperature below that of complete miscibility of the two.

2. A process as defined in claim 1 in which the oil treated is soybean oil.

3. A process of treating a natural glyceride oil containing break constituents, a portion of glycerides of fatty acids of a high degree of unsaturation and being adapted to air dry when spread as a film upon a surface to form a hard coating and a portion of glycerides of fatty acids of a low degree of unsaturation and having but slight capacity for air drying, which process comprises, refining said oil to remove said break constituents and then countercurrently flowing the oil through a body of furfural at a temperature below that of complete miscibility of the oil and the furfural, but sufficiently high to remove a substantial fraction of the more unsaturated glycerides as a furfural extract and separating the furfural phase from the glyceride phase and evaporating off the furfural from the extracted glycerides.

4. A process as defined in claim 3 in which the oil treated is soybean oil.

5. A process as defined in claim 3 in which the oil treated is soybean oil and the temperature is adjusted to extract out 40 to 75% of the oil in the furfural phase.

6. A process as defined in claim 3 in which the oil treated is in a proportion of 1 volume per 3 to 30 volumes of the furfural.

7. A process as defined in claim 3 in which the oil treated is soybean oil and is in a ratio of one volume to 3 to 30 volumes of the furfural.

8. In a process of obtaining a drying oil suitable for forming coating compositions, the steps which comprise subjecting soybean oil which has been pre-treated to remove break, to extraction by flowing furfural into an upper portion of an elongated extraction zone flowing the oil to be extracted into the same zone at a point below the point of introduction of furfural, removing the soybean raffinate oil at the top of the zone and removing furfural containing said drying oil as fraction in solution at the bottom of the zone and evaporating the furfural.

9. A process as defined in claim 8 in which a portion of extracted oil, after removal of at least a part of the solvent is reintroduced into the extraction system at a point below that of introduction of the solvent.

10. A process as defined in claim 8 in which the oil treated is soybean oil, furfural ratio is in a range of 3 to 30 volumes to 1 volume of oil, and the temperature is adjusted to extract out in the furfural phase 40 to 75% of the total oil.

11. In a process of treating soybean oil to separate therefrom a portion which is substantially enriched in a component of the natural soybean oil, which process comprises the steps of alkali refining soybean oil containing break constituents, then extracting said alkali refined oil by countercurrently flowing furfural therethrough, the resultant system of oil and furfural being maintained at a temperature below that of complete miscibility of the two, separating the resultant furfural phase from the oil phase and evaporating the furfural to obtain said portion.

12. The steps as defined in claim 11 in which the soybean oil is maintained at a temperature sufficient to extract out 40 to 75% of the oil in the furfural phase.

13. A process as defined in claim 11 in which the furfural is maintained in a ratio of 3 to 30 volumes per volume of oil.
